CLAIM

I claim the ornamental design for a headset, as shown and described.

DESCRIPTION

FIG. 1 is a perspective view of a headset embodying the invention.

FIG. 2 is a front view of the headset of FIG. 1.

FIG. 3 is a rear view of the headset of FIG. 1.

FIG. 4 is a first side view of the headset of FIG. 1.

FIG. 5 is a second side view of the headset of FIG. 1.

FIG. 6 is a top view of the headset of FIG. 1; and,

FIG. 7 is a bottom view of the headset of FIG. 1.

Portions of the headset shown in broken lines form no part of the claimed design.

1 Claim, 7 Drawing Sheets
